UNITED STATES PATENT OFFICE.

HERMAN J. H. HUBER, OF SCHENECTADY, NEW YORK, ASSIGNOR TO GENERAL ELECTRIC COMPANY, A CORPORATION OF NEW YORK.

SWITCHING APPARATUS.

Application filed January 29, 1923. Serial No. 615,507.

My invention relates to improvements in electrical switching apparatus, and particularly to a switch gear composed of parts especially designed for flexibility in construction, and for ease and safety of operation.

In the past, various means have been utilized to reduce the dangers incident to improper manipulations of switching apparatus. To this end the different parts of the apparatus have been so associated with each other as to insure that the various switching operations are performed in the proper sequence, the operating mechanisms of the oil switches and that of the disconnect switches provided for disconnecting the oil switch terminals from the line being interlocked to prevent operation of the disconnect switches until after the oil switches have been opened.

In order to facilitate inspection of the different parts of the switching apparatus and to permit the making of repairs, it has been proposed to mount the oil switch on a truck arranged to be moved away from the stationary part of the apparatus which comprises the leads through which power is received and supplied, the buses and their associated switches, and the potential transformer.

Between the stationary and movable part of the apparatus may be provided a panel adapted to support the necessary indicating and recording instruments. Whether it is desirable to mount the panel on the movable or stationary part of the apparatus must be determined by the characteristics of the particular installation. It is therefore desirable to have an arrangement of parts by means of which the panel may have its mounting changed to suit the particular installation in which it is used.

Due to the separation of the truck from the stationary part of the apparatus and the consequent exposure of the terminals through which energy is supplied and received, it is necessary to provide means of protection against accidental contact with these terminals which may be charged to a dangerous voltage. In accordance with my invention, improved means operated in response to the movement of the truck are provided for covering the terminals immediately upon withdrawal of the truck.

Complete withdrawal of the truck isolates the apparatus mounted thereon from any parts charged to a dangerous voltage. This not only greatly facilitates inspection of the apparatus but is of great assistance in the making of any repairs that may be necessary. In the past, it has happened that the truck has been brought back into operative relation with the stationary part of the apparatus without the tank of one of the switches being replaced and closure of the oil switches under these conditions has resulted in serious injury to the apparatus. In accordance with the present invention means are provided for preventing closure of the oil switch unless all the tanks have been replaced.

An object of my invention therefore is to provide means arranged to insure a greater degree of flexibility and safety in the operation of switching apparatus.

A further object is to provide an improved means for protecting the operator against accidental contact with live parts exposed by the separation of the movable part of the switching apparatus from the stationary part thereof.

A further object is to provide an interlocking mechanism which makes it impossible to operate the oil switches unless all the oil switch tanks have been replaced.

A still further object is to provide means by which the panel board may be either arranged to be moved with the truck or mounted on the stationary part of the apparatus as may be found desirable.

Other objects and advantages will become apparent as my invention is considered in detail.

My invention will be better understood from the following description taken in connection with the accompanying drawings and its scope will be pointed out in the appended claims.

Referring now to the drawing, Fig. 1 shows a sectional view of a switch gear, the live parts of which are encased in insulating material; Fig. 2 shows, partly in section, a view of a slightly different modification; Fig. 3 shows a sectional view of the movable truck together with the oil switch, and oil switch operating mechanism which is mounted upon it; Fig. 4 shows an interlocking mechanism which is provided for the pur-

pose of preventing withdrawal of the truck until the oil switches have been opened; Fig. 5 is a front elevation of the switch gear, the truck and panel board being shown 5 as partly cut away for the purpose of showing certain other parts; Figs. 6 and 7 show an arrangement of parts making it possible to attach the panel either to the stationary or movable parts of the apparatus as may 10 be found desirable; Fig. 8 shows the covers for the stationary disconnect contacts and the means by which they are operated; Fig. 9 shows means for preventing closure of the oil switches until all the tanks are in place, 15 and Fig. 10 shows the locking mechanism for preventing the opening or closing of the selector switches when the oil switch is closed.

The switch gear shown in Fig. 1 comprises 20 an oil switch 1 mounted on a truck 2 and connected in series with a current transformer 3 between the movable disconnect contacts 4 and 5 which are surrounded by insulating members 6 and 7 and arranged 25 to cooperate with the stationary disconnect contacts 8 and 9. The stationary disconnect contacts are surrounded by insulating hoods 10 and 11 and are conductively associated with the leads 12 and 13 respectively. Connected to the incoming lead 12 is a potential transformer 14 supported from the member 15 by brackets 16 and provided with a fuse 17, a resistor 18 and a lead 19. The potential transformer 14, together with 30 fuse 17 and the resistor 18 which are supported from a cover 21 by a suitable insulator 21', is submerged in oil contained within a casing 20 which supports the cover 21. Mechanically associated with the cover 21 are the contacts 22 and 23 arranged to 35 interrupt the circuit between the transformer 14 and the lead 12 when this cover is removed from the casing 20. The oil switch 1 is operated through a lever 24 pivoted at 40 and arranged to be raised and lowered by movement of the toggle 26-27. The toggle 26-27 is operated through a member 28 mechanically associated with the operating handle 29.

45 Conductively associated with the lead 13 are the switch blades 30 and 31 arranged to make contact with the stationary members 32 and 33 respectively for the purpose of connecting the lead 13 either to the bus 34 or the bus 35 as may be desired. The switch blade 30 is pivoted at 36 and is moved to make and break contact with the stationary contact 32 by means of an insulating link 37 with a bell crank 38 pivoted at 39 and inter- 50 connected by a link 40 with an operating lever 41 pivoted at 42 and connected to the operating handle 43 (see Figures 5, 6 and 7) by a suitable rod attached to the lever 41 at 44. The switch blade 31 is actuated by a 55 mechanism similar to that described in con-

nection with the switch blade 30, the respective operating handles being placed on opposite sides of the truck 2.

Operation of the bus selector switches 70 while the main oil switch is in closed position is prevented by means of an interlocking mechanism comprising a lever 74 supported by the bracket 73 and arranged to be rotated about the pin 76 in response to movement of the cross-head 48 to which the lever 74 is connected through rod 75 and pin 77. Upon the opposite end of the lever 74 is a cross-bar 72 which, in the closed position of the switch 1, contacts with the member 41 to prevent opening of the switch 80 30. The operating mechanism of the bus selector switch 31 is similarly arranged to be locked in either open or closed position by means of the bar 72.

85 Mounted above the tank of the switch 1 is a catch 45 arranged to prevent the closing of the oil switches unless all their tanks are in operative position. The catch 45 is biased to the left by a spring 46 (see Fig. 9) and is held against the action of this spring by 90 a projection 47 fixed to an upper edge of the tank of the switch 1 so that when the tanks are all in normal operating position the catches 45 are held out of contact with the cross-head 48 through which the oil switches in the different phases are actuated in response to movement of the operating handle 29. The oil switch in each phase is provided with a catch 45 and closure of the oil switches when any one of the tanks is 95 not in operative position is prevented by the catch which engages the cross-head 48 and prevents any movement of the operating mechanism.

100 Fig. 2 shows a modification in which the buses 49, 50 and 51 are connected directly to the stationary contact of the disconnect switch instead of through an oil immersed selector switch as in the modification shown by Fig. 1.

105 In Fig. 3, the movable part of the apparatus is shown as provided with a solenoid 52 arranged to operate the switch 1. With this arrangement, the solenoid 52 replaces the current transformer 3 which may be placed 110 to the rear of the stationary part of the apparatus.

115 In Fig. 4 is shown a mechanism for preventing withdrawal of the truck and opening of the disconnect switches while the oil switches are closed. Upon the truck 2 are 120 mounted rods 53 provided with handles 59 and with projections 54 arranged to lock the truck in a position to close the disconnect switches. Fixed to the rods 53 are the arms 55 arranged to rotate the disk 56 by means of rods 57. In the edge of the disk 56 is a notch 58 provided to cooperate with the lower end of the lever 27 for the purpose 125 of preventing rotation of the rods 53 when 130

the oil switch is closed. In the illustrated open position of the oil switch operating mechanism, the lever 27 is disengaged from the disk 56 so as to permit withdrawal of the truck and the consequent opening of the disconnect switches. With the parts constructed as shown it is impossible to move the truck either to open or close the disconnect switches when the associated oil switches are in closed position.

For the purpose of more clearly showing the relation between the truck 2, the stationary contacts 8 and 9 of the disconnect switches, and the contact covers 60 the truck 15 and panel are shown in Fig. 5 as partly cut away. The covers 60 of the two sets of contacts 8 and 9 are interconnected by a rod 61 (see Fig. 8) and simultaneously operated in response to movement of the member 62 which is fixed at one end to the truck 2 and at the other end is provided with a roller 63 arranged to cooperate with a lever 64 rotatably mounted on the shaft 66. The lever 64 is resiliently connected with the lever 65 through a spring 67 which permits the roller 63 to travel some distance after the cover 60 has been completely raised and further rotation of the shaft 66 is impossible. Lowering of the cover 60 upon withdrawal of the truck 2 is insured by contact of the roller 63 with the lever 65.

In Figs. 6 and 7 is shown an arrangement of parts which makes it possible to attach the panel 68 either to the stationary or movable part of the apparatus. As shown in Fig. 6 the panel 68 is attached to the truck by means of bolts 69 and 70. As shown in Fig. 7, the panel is attached to the stationary part of the structure by means of bolts 71. The position of the various parts upon withdrawal of the truck 2 are indicated by dotted lines. Whether the panel is to be attached to the truck or to the stationary part of the apparatus is a question which can be decided only when the requirements of the particular installation are known. It is, therefore, of great advantage to have an arrangement by which the mounting of the panel may be changed as desired.

What I claim as new and desire to secure by Letters Patent of the United States, is:

1. An electric switching apparatus of the type wherein a circuit is interrupted by an oil switch mounted on a truck movable to make and break contact between the stationary and movable contacts of disconnect switches arranged to connect the oil switch terminals with the incoming and outgoing lines comprising a protective cover associated with the stationary contacts of said disconnect switches and means comprising a member having a resilient connection with said cover for positively moving said cover into and out of protective position in response to movements of said truck.

2. An electric switching apparatus of the type wherein a circuit is interrupted by an oil switch mounted on a truck movable to make and break contact between the stationary and movable contacts of disconnect switches arranged to connect the oil switch terminals with the incoming and outgoing lines comprising a protective cover for a plurality of the stationary contacts of said disconnect switches pivotally mounted adjacent thereto on an axis at right angles to the line of movement of said truck and means comprising a member having a resilient connection with said cover for positively moving said cover into and out of protective position in response to movements of said truck.

3. An electric switching apparatus of the type wherein a circuit is interrupted by an oil switch mounted on a truck movable to make and break contact between the stationary and movable contacts of disconnect switches arranged to connect the oil switch terminals with the incoming and outgoing lines, comprising a cover for said stationary contacts, a shaft upon which said cover is mounted, a lever rigidly associated with said shaft, a second lever movable about said shaft and resiliently connected with said first mentioned lever, and a member fixed to said truck and arranged to cooperate with said levers to raise and lower said cover.

4. An electric switching apparatus of the type wherein a circuit is interrupted by an oil switch mounted on a truck movable to make and break contact between the stationary and movable contacts of disconnect switches arranged to connect the oil switch terminals with the incoming and outgoing lines, comprising a cover for said stationary contacts, and means forming a resilient operative connection between said truck and said cover arranged to permit continued movement of said truck after said cover has been raised.

5. An electric switching apparatus of the type wherein a circuit is interrupted by oil switches mounted on a truck movable to make and break contact between the stationary and movable contacts of disconnect switches arranged to connect the oil switch terminals with the incoming and outgoing lines, comprising a cross head through which the oil switches in the different phases are operated in response to movement of a single operating mechanism, a spring operated catch adjacent the tank of each oil switch and biased to a position in which it engages said cross head to prevent closure of said oil switches, and oil switch tanks having projections arranged to cooperate with said catches to disengage them from said cross head.

6. An electric switching apparatus comprising a stationary part and a truck-mounted movable oil switch, said stationary part

110

115

120

125

130

and said oil switch having contacts arranged to connect the oil switch terminals with the incoming and outgoing lines, and a panel between the oil switch and the stationary 5 part having means whereby it may be attached either to said truck or to the stationary part of the apparatus.

7. An electric switching apparatus comprising a tank containing insulating liquid, 10 contacts immersed therein, a rod movable to operate said contacts, a catch, means arranged to cooperate with said catch for preventing movement of said rod, and means operated by movement of said tank to render 15 said catch incapable of preventing movement of said rod.

8. An electric switching apparatus comprising a plurality of tanks movable into operative and inoperative positions and each 20 containing a set of contacts operable to make and break a circuit, a rod extending through a wall of each tank and arranged to operate the contacts within the same, and means arranged to cooperate with said rods for 25 preventing operation of any of said contacts when any of said tanks are not in operative position.

9. An electric switching apparatus comprising a plurality of tanks movable into operative and inoperative positions and each 30 containing a set of contacts operable to make and break a circuit, a rod extending through a wall of each tank and arranged to operate the contacts within the same, a plurality of catches each mounted in proximity to one 35 of said tanks, means arranged to cooperate with said catches for preventing closure of any of said contacts when any of said tanks are not in operative position, and means operable in response to movement of said 40 tanks for rendering said catches ineffective.

10. An electric polyphase switching apparatus comprising fixed contacts, a truck having contacts adapted to cooperate therewith in accordance with the position of the 45 truck, separate phase switches carried by the truck, an enclosing tank for each phase switch removable to an inoperative position, and means for preventing the closing of any of said switches when the tank of any switch 50 is in inoperative position.

In witness whereof, I have hereunto set my hand this 27th day of January, 1923.

HERMAN J. H. HUBER.
